UNITED STATES PATENT OFFICE.

CHARLES A. LUNDGREN, OF DETROIT, MICHIGAN, ASSIGNOR TO BURROUGHS ADDING MACHINE COMPANY, OF DETROIT, MICHIGAN, A CORPORATION OF MICHIGAN.

ADDING AND LISTING MACHINE.

1,195,598.

Specification of Letters Patent. Patented Aug. 22, 1916.

Application filed September 4, 1914. Serial No. 860,291.

To all whom it may concern:

Be it known that I, CHARLES A. LUNDGREN, a citizen of the United States, residing at Detroit, in the county of Wayne 5 and State of Michigan, have invented certain new and useful Improvements in Adding and Listing Machines, of which the following is a specification.

The present invention relates to so-called 10 tally-roll equipments for adding and listing machines and is in the nature of an improvement upon the prior invention of Fred F. Main which has been made the subject of prior Patent 1,173,293, issued February 29, 15 1916. As in the case of Main's said invention I propose to have the tally roll come 20 into printing position automatically as an incident to the taking of totals, and also to provide for its use at any time at the will 25 of the user of the machine. My improvements pertain to the character of means employed for driving the tally-roll carriage back to normal or non-printing position and to the character of means for controlling the 30 positioning of the tally-roll carriage for printing purposes. I aim to provide means of a more positive character and capable of more compact and unobtrusive arrangement than heretofore for applying power to re- 35 store the tally-roll carriage to non-printing position; and as to control in positioning for printing I aim to provide for such positioning as a preliminary to operation of the machine proper, and I furthermore aim to 40 provide for indefinitely maintaining the 45 tally-roll carriage in printing position as well as for indefinitely maintaining it in non-printing position. In addition to this I provide for establishing two different printing positions for the purpose of distinguishing between imprints of items or amounts and imprints of totals or sub-totals on the tally strip in case the conditions are such as to preclude the printing upon the strip of the usual sign to distinguish totals and sub-totals.

With these and incidental objects in view the invention consists in certain novel features of construction and combination of 50 parts, the essential elements whereof are recited in the appended claims and a preferred form of embodiment of which is illustrated in the accompanying drawings forming part of this specification.

In said drawings, Figure 1 represents in 55 left side elevation an adding and listing machine of the well-known Burroughs type having applied thereto a tally-roll equipment which embodies my present invention; Fig. 2 is a broken rear elevation of said machine showing the tally roll in non-printing position; Fig. 3 is a rear elevation minus the main paper carriage and with the tally-roll carriage in printing position; Fig. 4 is a vertical section on the line 4—4 of Fig. 3; 60 Fig. 5 is a right side elevation of parts appearing in rear elevation at the lower left hand corner of Fig. 3; Fig. 6 is a sectional and somewhat fragmentary plan view taken substantially on line 6—6 of Fig. 3; Fig. 7 65 is a detail sectional plan view on the order of the right-hand portion of Fig. 6 but illustrating a slightly different condition; Fig. 8 is a fragmentary sectional rear elevation representing normal conditions; Fig. 9 is a 70 sectional left side elevation of certain parts which appear normal in Fig. 1, whereas in this present figure the total key is shown almost fully depressed; Fig. 10 is a similar view with the special tally key depressed; 75 Fig. 11 shows an example of work.

The adding and listing machine proper is 80 so well known through disclosures of prior patents and commercial usage as to require no special description, though reference will 85 be made to some familiar parts with which those introduced for carrying out my present invention directly coöperate.

The back panel of the machine casing is 90 designated by the numeral 2 and there is 95 fastened to it as usual a track 3 for the laterally shifting main paper carriage 4. The usual cradle 5 is mounted upon this carriage and supports the roller platen 6. Said cradle is here shown with a holder 7 for 100 sheet paper such, for example, as ledger sheets with which the tally roll equipment is especially desirable. This equipment comprises an upper roll holder 8 and a lower roll holder 9 connected by a thin metal plate 10 which runs through the narrow space between the carriage track 3 and the panel 2. A chute 11 is arranged at the upper part of this plate and the tally strip is threaded through this chute and thence through an 105 opening 12 in the plate 10 (Fig. 4) so as to run close to the paper overlying the roller platen 6. Just below this another chute 13

is formed upon the plate 10 to envelop the tally strip where it passes between the carriage track and the back panel of the machine casing.

5 The type plates 618 of the machine proper strike through the opening 12 to reach the roller platen and the paper overlying the same, and, when the tally roll is in printing position, the tally strip itself which is carbonized on the rear side so that the imprint made upon it will be duplicated upon the sheet paper. The tally strip runs down out of the chute 13 under a guide roller 14 and over a table 15 to the under side of a take-up roller 16 in the lower roll holder 9, a pressure roller 17 being suitably arranged below said take-up roller 16 so that the strip may be fed by the turning of the latter. This is accomplished through the medium 10 of a ratchet 18 on said take-up roller and a pawl 19 carried by an arm 20 having a laterally projecting stud 21 arranged to be operated upon by the familiar feed lever 122 of the machine proper when the tally 15 roll is moved over into printing position. Normally this stud 21 stands off to the left as the parts appear in Fig. 2, so that said feed lever 122 does not affect it. It will of course be understood that there should be no 20 feed of the tally strip except when it is in printing position or in connection with the printing upon the strip.

The above described tally roll holder is carried upon a rod 30 being secured thereto 25 by set screws 31 in bosses on the side plates of the lower roll holder 9. The rod 30 is conveniently arranged to slide through the lugs 32 on the base of the machine and the lugs 33 on the back panel of the machine 30 which lugs constitute parts of hinges by which said back panel is mounted on said base. The rod takes the place of the usual pintles and it will be noted that this arrangement makes for compactness and the 35 minimum of projection of the tally roll structure from the rear of the machine. A spring 40 connecting one of the set screws 31 with a screw stud in one of the lugs 33 tends to pull the whole tally roll carriage to the right as the parts are seen in Figs. 2 and 40 3 and thus move it into printing position.

Referring to the feature of my present invention first mentioned in the opening statement of this specification, to wit, the character of means for driving the tally roll carriage back to non-printing position, which means will ordinarily serve to normally restrain the spring, I mount a pivot screw stud 50 in the back panel 2 (Figs. 2 and 3) 45 and suspend from it a lever 51 which operates upon a roller stud 52 carried by a collar 53 which is secured to the slide rod 30. On the same stud 50 I mount a bell crank lever which has a short laterally extending arm 54 having a gear segment 55, which meshes

with a short rack 56 formed upon or secured to the upper part of the vertically sliding line-space plate 89 which is itself a familiar element of these machines. The aforesaid feed lever 122 is coupled to said plate as 70 usual so that the latter is reciprocated in every operation of the machine. Therefore the said bell crank lever is oscillated in every operation of the machine. It has a longer depending arm 57 which extends 75 along the lever 51 and carries at its lower end a pivoted pawl 58 notched to engage a stud 51^a on said lever, the engagement being enforced by a spring 59 which connects the tail of the pawl with an upper portion of 80 the bell crank arm 57. So long as this engagement exists the lever will oscillate with the bell crank. The normal condition is illustrated in Fig. 2, the plate 89 being elevated and the lower arm of the bell crank 85 consequently swung over to the left as the parts are there seen and the lever 51 correspondingly swung so that it holds the tally roll carriage in non-printing position. It will be seen that if the pawl 58 is disengaged 90 from the stud 51^a the restraint imposed upon the tally roll carriage by the lever 51 will be removed, and the spring 40 will be permitted to pull the tally roll carriage into printing position unless otherwise restrained as by the latch hereinafter described. Fig. 3 illustrates the effect of disengaging the pawl and unlatching the carriage, the latter having been pulled to printing position by its spring and having correspondingly swung the lever 51 over to the right as the parts are seen in this figure of the drawing. Upon operation of the machine the bell crank 54—57 will be rocked and the pawl reengaged with the stud 51^a 105 so that in the last half cycle of operation of the machine the lever 51 will be forcibly swung back to the left and will restore the tally roll carriage to non-printing position.

It will be seen that the above described 110 mechanism for applying power to restore the tally roll carriage is compact and unobtrusive lying close against the back panel of the machine and is direct and positive in its operation. Furthermore, it will be noted that, in line with the second stated object of 115 my present invention, the separable connection between the bell crank and the restoring lever provides for the shifting of the tally roll carriage into printing position as a preliminary to the operation of the machine proper.

Referring next to the means for bringing the tally roll into action at will, a lever 70 (Fig. 1) is pivoted at its middle on a frame 125 stud 2^a and its rear arm extends under the pawl 58 which is elongated into a tapered finger 58^a with a suitable curvature of its under edge to provide for its riding over the top edge of the lever 70 in ordinary op- 130

erations of the machine without any resultant disengagement of the pawl from the stud 51^a and also for the riding of the stud 51^a along its under edge. The forwardly 5 extending arm of the lever 70 is coupled to a link 71 which extends up to the front part of the machine and is there coupled to the stem 72 of a key 73 at the lower left hand corner of the keyboard. This stem 10 is bifurcated at its lower end to engage a guiding frame stud 2^b and is permitted sufficient oscillation to engage its notch 74 under the upper keyboard plate when it is desired to keep the key down. Depression 15 of this key will obviously rock the lever 70 and elevate the pawl 58 disengaging it from the stud 51^a. Depression of said key also effects an unlatching of the tally roll carriage. A latch plate 75 is hung from the 20 rear end of said lever and guided at its lower end in the slot of a collar 78 surrounding the rod 30 and carried by a bushing 79 (Fig. 6) having a drive fit through the adjacent lugs 33. Normally a forward 25 portion of the latch plate above a horizontal shoulder 75^a thereof (Figs. 1, 8 and 9) occupies a notch 30^a in the upper side of said rod at the right hand end thereof as the parts are viewed in Figs. 7 and 8, there- 30 by holding the rod against movement by its spring 40. Depression of the key 73 results in lifting the latch plate (Fig. 10) and freeing the rod so that it and the tally roll carriage may be shifted over until a 35 leather washer 80 adjacent the collar 53 strikes as a stop shoulder against one of the lugs 32, as shown in Fig. 6 and also in Fig. 3. This fixes the printing position of the tally roll carriage for items or amounts, and 40 it will be obvious that the tally roll carriage may be kept in its printing position indefinitely by latching down the key 73 or holding it down, for in such case the pawl 58 remains uncoupled from the lever 51 so that 45 the bell crank 54—57 will oscillate idly.

Referring next to the bringing into action of the tally roll as an incident to the taking of a total or sub-total, the reference numeral 265 designates the familiar total key, and 50 the reference numeral 265^s, the familiar sub-total key, depression of either of which effects a rearward movement of the familiar link 226 which performs its customary function of operating a release bail for restor- 55 ing any depressed amount keys 291 of the machine proper. I utilize this link 226 for effecting release of the tally roll carriage. It is slightly modified by making a depression 226^a in the under side of its slot, the 60 purpose of which depression will presently appear.

I mount a V-shaped stud 90 in the link 226 for coöperation with the V-shaped upper extremity of a lever 91 which is pivoted 65 intermediate its ends upon a frame stud 2^c,

as shown in Figs. 1, 9 and 10. A spring 92 holds the upper arm of this lever normally forward and against a stop stud 93. The lower arm of the lever terminates in a forwardly extending cam finger 91^a which is 70 designed to coöperate with a stud 70^c on the rear arm of the lever 70. Rearward swinging of the upper arm of the lever 91 and corresponding forward swinging of the lower arm causes the upper edge of said 75 finger to act upon the stud 70^c with a camming effect and lift the rear arm of the lever 70. The upper extremity of the lever 91 normally stands in rear of the V-shaped lug 90 as shown in Fig. 1 so that depression 80 of total or sub-total key will effect such rocking of the lever 91. The effect is to disengage the pawl 58 from the lever 51, as in the case of depression of the key 73, and to also raise the latch plate 75. How- 85 ever, the movement is not so extensive as that produced by depression of the key 73, (compare Figs. 9 and 10) the purpose being to bring about a slightly different printing position of the tally roll strip in order that 90 the imprint of a total or sub-total thereon may be distinguished from that of an item or amount by a slight difference in lateral position on the strip. A special construction of the latch plate comes into consider- 95 ation here and also a special construction of the slide rod 30. The latter is flattened along its rear side at the right hand end (Fig. 6) leading up to a shoulder 30^d so located as to determine the lateral position 100 of the rod and the tally roll carriage differ- 105 ently from that determined by abutment of the aforesaid leather washer 80 against the lug 33. This is illustrated in Fig. 7 which represents the condition resulting 110 from depression of total or sub-total key. In this connection a portion of the latch plate 75 serves as a stop for the tally roll carriage, to wit, a depending portion 75^b which passes down to the rear of the rod 30. 115 A forward vertical edge 75^c of this down- 120 ward extension fits close to the flattened rear surface of the rod 30 and the portion of the latch plate adjacent this edge serves as an abutment for the shoulder 30^d to en- 125 counter when the latch plate is lifted by the total or sub-total key. When lifted by the "tally" key 73 this portion of the latch plate is raised entirely above the rod (Fig. 10) so that the latter and the tally roll carriage may move farther over or until the leather washer 80 comes up against the lug 33. For the purpose of properly confining the latch plate in its up-and-down move- 130 ments a keeper plate 92 is fastened to the collar 78 and formed with a bent-over ear 92^a extending in rear of the downward ex- 135 tension 75^b of the latch plate which exten- 140 sion is sufficiently elongated to remain en- 145 gaged with said ear when the latch plate is

raised to its highest extent. This lowermost portion of the latch plate is cut back from the abutment portion adjacent the vertical edge 75° so as not to in any way obstruct the 5 rod 30.

As the printing of a total or sub-total would necessarily be an occasional performance requiring the interposition of the tally strip for the one operation and its immediate restoration to non-printing position, the lever 91 is not held displaced throughout the depression of total or sub-total key, it being understood that in all of these machines having the construction here shown 10 these keys remain down throughout the operation of the machine. Now it is essential in the present construction, in order that the tally roll shall be restored to non-printing position, that the pawl 58 reengage the stud 51^a at the conclusion of the first half cycle of operation of the machine. Therefore the before-mentioned V-shaped stud 90 on the link 226 is so related to the upper extremity of the lever that said stud may wipe past the 15 point of the lever and permit the latter to be restored. The arcuate movements of the lever and the link 226 provide for the escape of the lug 90 past the point of the lever. As the parts appear in Fig. 9 this is just about 20 to occur with completion of depression of the total key. Of course upon the freeing of this lever its lower arm swings back and releases the lever 70. A spring 99 is applied to the forward arm of the latter to insure 25 its prompt return to or toward normal and upon such release of said lever its rear arm drops and the pawl 58 bears down upon the stud 51^a ready to immediately engage the same when the bell crank 54—57 reaches the 30 limit of its initial swing upon operation of the machine. Likewise the latch plate 75 lowers upon the rod 30 so that when the lever 51 is restored by the said bell crank in the last half cycle of the operation of the 35 machine proper, the tally roll carriage will become latched in its non-printing position. At the conclusion of the operation the total keys are restored and the stud 90 rides over the point of the lever 91 and drops in front of 40 it, this being permitted by the before-mentioned slight depression 226 in the under side of the slot of the link. To insure the repositioning of the said stud in front of the lever a spring 100 is applied to the link 45 226 tending to pull it down.

The distinguishing of totals or sub-totals from items or amounts by different lateral positions on the tally strip (see example of work Fig. 11) is of consequence under conditions such as may exist and would make the usual special printing of signs to distinguish total and sub-totals unavailable. For example, in a machine of large keyboard capacity, such as is now commonly employed 60 and in which one or more "splits" or sub-

divisions of the recording mechanism were provided for and at the same time a narrow tally strip was in use, the imprint of a total amount to the left of a split or subdivision would be separated by a considerable space 70 from the imprint of the special sign at the extreme right and the tally strip might not be wide enough to take the sign imprint. Where both items and totals are printed on a tally strip it is desirable that they be 75 readily distinguishable and the above described arrangement provides for this even in cases where the customary sign printing cannot be relied upon,—a total or sub-total being printed slightly out of line with items 80 or a little to the left, as the total 421264 appears in Fig. 11.

It is desirable that the machine be available for use without the tally roll equipment and therefore I provide for keeping 85 the latter indefinitely out of commission at the will of the operator. To this end I provide a notch 30° near the left hand end of the rod 30 as the parts are viewed in Fig. 3, and arrange a latch 105 to engage said 90 notch as illustrated in Fig. 2. This latch is pivoted upon a plate 106 which is secured to a collar 107 on a bushing 108 having a drive fit in the adjacent lug 33. A spring 110 is applied to this latch so that it will cross the 95 pivot thereof and thus serve either for holding it in effective position or in the ineffective position illustrated in Fig. 5 against a stud 111 to which one end of the spring 100 100 is applied.

I claim:

1. In a machine of the class described, the combination with printing mechanism and a paper holder; of a supplemental paper holder shiftable relative to the main paper holder between pre-defined positions in and out of juxtaposition to the printing mechanism; a spring for moving said supplemental holder into printing position; means for restraining said spring; a key and connections 105 for disabling said latter means; a prime mover and connections for returning the said holder to normal position; and means for disabling said connections by said key.

2. In a machine of the class described, the combination with printing mechanism and a paper holder; of a supplemental paper holder shiftable relative to the main paper holder between pre-defined positions in and out of juxtaposition to the printing mechanism; a spring for moving said supplemental holder into printing position; means for restraining said spring; a key and connections for disabling said latter means; a prime mover and connections for returning the said holder to normal position; and means for disabling said connections by said key with provisions for automatically re-establishing them.

3. In a machine of the class described, the

combination with printing mechanism and a paper holder; of a supplemental paper holder shiftable relative to the main paper holder between pre-defined positions in and out of juxta-relation to the printing mechanism; a spring for moving said supplemental holder into printing position; means for restraining said spring; a key and connections for disabling said latter means; a prime mover and connections for returning the said holder to normal position; and means for momentarily disabling said connections by said key.

4. In a machine of the class described, the combination with printing mechanism and a paper holder; of a supplemental paper holder shiftable relative to the main paper holder between predefined positions in and out of juxta-relation to the printing mechanism; a spring for moving said supplemental holder into printing position; means for restraining said spring; a key and connections for disabling said latter means; a prime mover and connections for returning the said holder to normal position; and pass-by means for disabling said connections by said key.

5. In a machine of the class described, the combination with printing mechanism and a paper holder; of a supplemental paper holder shiftable relative to the main paper holder between predefined positions in and out of juxta-relation to the printing mechanism; a spring for moving said supplemental holder into printing position; means for restraining said spring; a key and connections for disabling said latter means; and a prime mover and connections for returning the said holder to normal position, including a vibrating arm carrying a pawl, and a lever engaged by said pawl, the latter adapted to be displaced by said key connections.

6. In a machine of the class described, the combination with printing mechanism and a paper holder; of a supplemental paper holder shiftable relative to the main paper holder between pre-defined positions in and out of juxta-relation to the printing mechanism with provision for setting the said supplemental holder in either of two printing positions.

7. In a machine of the class described, the combination with printing mechanism and a paper holder; of a supplemental paper holder shiftable relative to the main paper holder between pre-defined positions in and out of juxta-relation to the printing mechanism with provision for setting the said supplemental holder in either of two printing positions; and separate keys and connections for predetermining the printing position thereof.

8. In a machine of the class described, the combination with printing mechanism and

a paper holder; of a supplemental paper holder shiftable relative to the main paper holder between predefined positions in and out of juxta-relation to the printing mechanism; a spring for moving said supplemental holder to printing position; and means for stopping it at either of two printing positions.

9. In a machine of the class described, the combination with printing mechanism and a paper holder; of a supplemental paper holder shiftable relative to the main paper holder between pre-defined positions in and out of juxta-relation to the printing mechanism; a spring for moving said supplemental holder to printing position; means for stopping it at either of two printing positions; and keys controlling said means.

10. In a machine of the class described, the combination with printing mechanism and a paper holder; of a supplemental paper holder shiftable relative to the main paper holder between pre-defined positions in and out of juxta-relation to the printing mechanism, said holder having a differentially shouldered slide rod; a movable abutment to coact with one shoulder thereof, a fixed abutment to coact with another shoulder thereof, and keys for displacing the movable abutment different extents.

11. In a machine of the class described, the combination with printing mechanism and a paper holder; of a supplemental paper holder shiftable relative to the main paper holder between pre-defined positions in and out of juxta-relation to the printing mechanism; said holder having a differentially shouldered slide rod; a movable abutment to coact with one shoulder thereof to keep the holder out of printing position and with another shoulder to stop the holder at one of its printing positions; a fixed abutment to coact with a third shoulder of the slide rod to stop the shoulder in another of its printing positions; and keys controlling said movable abutment.

12. In a machine of the class described, the combination with printing mechanism and a paper holder; of a supplemental paper holder shiftable relative to the main paper holder between pre-defined positions in and out of juxta-relation to the printing mechanism, said holder having a differentially shouldered slide rod; a movable abutment to coact with one shoulder thereof; a fixed abutment to coact with another shoulder thereof; a lever connected to said movable abutment; a key for rocking the lever to the maximum extent; and a key and connections for rocking said lever to a lesser extent.

13. In a machine of the class described, the combination with printing mechanism and a paper holder; of a supplemental paper holder shiftable relative to the main paper holder between pre-defined positions in and

out of juxta-relation to the printing mechanism, said holder having a differentially shouldered slide rod; a movable abutment to coact with one shoulder thereof to keep the 5 holder out of printing position and with another shoulder to stop the holder at one of its printing positions; a fixed abutment to coact with a third shoulder of the slide rod to stop the shoulder in another of its printing 10 positions; a lever connected to said movable abutment; a key for rocking the lever to the maximum extent; and a key and connections for rocking said lever to a lesser extent.

14. In a machine of the class described, the combination with printing mechanism and a paper holder; of a supplemental paper holder shiftable relative to the main paper holder between pre-defined positions in and 20 out of juxta-relation to the printing mechanism, said holder having a differentially shouldered slide rod; a movable abutment to coact with one shoulder thereof to keep the holder out of printing position and with 25 another shoulder to stop the holder at one of its printing positions; a fixed abutment to coact with a third shoulder of the slide rod to stop the shoulder in another of its printing 30 positions; a lever connected to said movable abutment; a key for rocking the lever to the maximum extent; a second lever bearing a camming relation to the first-mentioned lever; and a key and connections for operating said second lever.

15. In a machine of the class described, the combination with printing mechanism and paper holder; of a supplemental paper holder shiftable relative to the main paper holder between pre-defined positions in and out of 40 juxta-relation to the printing mechanism; a spring for moving said supplemental holder to printing position; means for stopping it at either of two printing positions; a prime mover and connections for returning the 45 said holder to normal position; and means for disabling said connections.

16. In a machine of the class described, the combination with printing mechanism and a paper holder; of a supplemental paper holder shiftable relative to the main paper holder between pre-defined positions in and 50 out of juxta-relation to the printing mechanism; a spring for moving said supplemental holder to printing position; means 55 for stopping it at either of two printing positions; keys controlling said means; a prime mover and connections for returning the said holder to normal position; and means operated by said keys for disabling 60 said connections.

17. In a machine of the class described, the combination with printing mechanism and a paper holder; of a supplemental paper holder shiftable relative to the main paper holder 65 between pre-defined positions in and out of

juxta-relation to the printing mechanism, said holder having a differentially shouldered slide rod; a movable abutment to coact with one shoulder thereof; a fixed abutment to coact with another shoulder thereof; 70 keys for displacing the movable abutment different extents; a prime mover and connections for returning the said holder to normal position; and means operated by said keys for disabling said connections. 75

18. In a machine of the class described, the combination with printing mechanism and a paper holder; of a supplemental paper holder shiftable relative to the main paper holder between pre-defined positions in and 80 out of juxta-relation to the printing mechanism, said holder having a differentially shouldered slide rod; a movable abutment to coact with one shoulder thereof to keep the holder out of printing position and with 85 another shoulder to stop the holder at one of its printing positions; a fixed abutment to coact with a third shoulder of the slide rod to stop the shoulder in another of its printing positions; keys controlling said 90 movable abutment, a prime mover and connections for returning the said holder to normal position; and means operated by said keys for disabling said connections. 90

19. In a machine of the class described, the combination with printing mechanism and a paper holder; of a supplemental paper holder shiftable relative to the main paper holder between pre-defined positions in and out of juxta-relation to the printing mechanism, said holder having a differentially shouldered slide rod; a movable abutment to coact with one shoulder thereof; a fixed abutment to coact with another shoulder thereof; 100 a lever connected to said movable abutment; a key for rocking the lever to the maximum extent; a key and connections for rocking said lever to a lesser extent; a prime mover and connections for returning the said holder to normal position; and means operated by said keys for disabling said connections. 110

20. In a machine of the class described, the combination with printing mechanism and a paper holder; of a supplemental paper holder shiftable relative to the main paper holder between pre-defined positions in and out of juxta-relation to the printing mechanism, said holder having a differentially shouldered slide rod; a movable abutment to coact with one shoulder thereof to keep the holder out of printing position and with another shoulder to stop the holder at one of its printing positions; a fixed abutment to coact with a third shoulder of the slide rod to stop the shoulder in another of its printing positions; a lever connected to said movable abutment; a key for rocking the lever to the maximum extent; a key and connections for rocking said lever to a lesser extent. 125 130

tent; a prime mover and connections for returning the said holder to normal position; and means operated by said keys for disabling said connections.

21. In a machine of the class described, the combination with printing mechanism and a paper holder; of a supplemental paper holder shiftable relative to the main paper holder between pre-defined positions in and out of juxta-relation to the printing mechanism, said holder having a differentially shouldered slide rod; a movable abutment to coact with one shoulder thereof to keep the holder out of printing position and with another shoulder to stop the holder at one of its printing positions, a fixed abutment to coact with a third shoulder of the slide rod to stop the shoulder in another of its printing positions; a lever connected to said movable abutment; a key for rocking the lever to the maximum extent; a second lever bearing a camming relation to the first-mentioned lever; a key and connections for operating said second lever; a prime mover and connections for returning the said holder to normal position; and means operated by said keys for disabling said connections.

22. In a machine of the class described, the combination with printing mechanism and a paper holder; of a supplemental paper holder shiftable relative to the main paper holder between pre-defined positions in and out of juxta-relation to the printing mechanism, said holder having a differentially shouldered slide rod; a movable abutment to coact with one shoulder thereof to keep the holder out of printing position and with another shoulder to stop the holder at one of its printing positions; a fixed abutment to coact with a third shoulder of the slide rod to stop the holder in another of its printing positions; a lever connected to said movable abutment; a key for rocking the lever to the maximum extent; a second lever bearing a camming relation to the first-mentioned lever; a key and connections having pass-by engagement with said second lever; a prime mover and connections for returning the said holder to normal position; and means operated by said keys for disabling said connections.

23. In a machine of the class described, the combination with printing mechanism and a paper holder; of a supplemental paper holder shiftable relative to the main paper holder between pre-defined positions in and out of juxta-relation to the printing mechanism, said holder having a differentially shouldered slide rod; a movable abutment to coact with one shoulder thereof to keep the holder out of printing position and with another shoulder to stop the holder at one of its printing positions; a fixed abutment to coact with a third shoulder of the slide to

stop the holder in another of its printing positions; and a prime mover and connections for returning the said holder to normal position, including a vibrating arm carrying a pawl, and a lever engaged by said pawl, 70 the latter adapted to be displaced by said keys.

24. In a machine of the class described, the combination with printing mechanism and a paper holder; of a supplemental paper holder shiftable relative to the main paper holder between pre-defined positions in and out of juxta-relation to the printing mechanism, said holder having a differentially shouldered slide rod; a movable 80 abutment to coact with one shoulder thereof; a fixed abutment to coact with another shoulder thereof; a lever connected to said movable abutment; a key for rocking the lever to the maximum extent; a key and 85 connections for rocking said lever to a lesser extent; and a prime mover and connections for returning the said holder to normal position, including a vibrating arm carrying a pawl, and a lever engaged by said pawl, 90 the latter being engaged by the first-mentioned lever.

25. In a machine of the class described, the combination with printing mechanism and a paper holder; of a supplemental paper holder shiftable relative to the main paper holder between pre-defined positions in and out of juxta-relation to the printing mechanism, said holder having a differentially shouldered slide rod; a movable abutment to coact with one shoulder thereof to keep the holder out of printing position and with another shoulder to stop the holder at one of its printing positions; a fixed abutment to coact with a third shoulder of the slide rod to stop the holder in another of its printing positions; a lever connected to said movable abutment; a key for rocking the lever to the maximum extent; a key and 100 connections for rocking said lever to a lesser extent; and a prime mover and connections for returning the said holder to normal position, including a vibrating arm carrying a pawl, and a lever engaged by said pawl, 105 the latter being engaged by the first-mentioned lever.

26. In a machine of the class described, the combination with printing mechanism and paper holder; of a supplemental paper holder shiftable relative to the main paper holder between pre-defined positions in and out of juxta-relation to the printing mechanism; a spring for moving said supplemental holder into printing position; a reciprocating member normally opposing said spring; a prime mover; and means for coupling and uncoupling the same and the said reciprocating member.

27. In a machine of the class described, the combination with printing mechanism 130

and paper holder; of a supplemental paper holder shiftable relative to the main paper holder between pre-defined positions in and out of juxta-relation to the printing mechanism; a spring for moving said supplemental holder into printing position; a lever opposing said spring; a prime mover; a vibrating arm operatively connected therewith; and means for coupling and uncoupling the arm and the lever.

28. In a machine of the class described, the combination with printing mechanism and paper holder; of a supplemental paper holder shiftable relative to the main paper holder between pre-defined positions in and out of juxta-relation to the printing mechanism; a spring for moving said supplemental holder into printing position; a lever opposing said spring; a reciprocating plate; a bell crank lever geared to said plate; and means for coupling and uncoupling said

bell crank lever and the first-mentioned lever.

29. In a machine of the class described, the combination with printing mechanism and paper holder; of a supplemental paper holder shiftable relative to the main paper holder between pre-defined positions in and out of juxta-relation to the printing mechanism; a spring for moving said supplemental holder into printing position; a lever opposing said spring; a reciprocating plate; a bell crank lever geared to said plate; and means for coupling and uncoupling said bell crank lever and the first-mentioned lever comprising a spring-held pawl on one lever and a stud on the other.
